UNITED STATES PATENT OFFICE.

WILLIAM M. SCOTT, OF PHILADELPHIA, PENNSYLVANIA, ASSIGNOR TO THE CUTTER ELECTRICAL & MANUFACTURING COMPANY, OF PHILADELPHIA, PENNSYLVANIA, A CORPORATION OF NEW JERSEY.

ELECTRICAL SWITCH.

No. 854,436.

Specification of Letters Patent.

Patented May 21, 1907.

Application filed May 26, 1904. Serial No. 209,827.

To all whom it may concern:

Be it known that I, WILLIAM M. SCOTT, a citizen of the United States, residing in the city and county of Philadelphia and State of Pennsylvania, have invented a new and useful Electrical Switch, of which the following is a specification.

My invention relates to electrical switches, more particularly those which are required to carry and interrupt electric currents of very great magnitudes, such as currents of thousands of amperes.

My invention relates to high capacity electrical switches which are to be closed or operated manually, or otherwise, my invention comprising means for gaining mechanical advantage, whereby a switch of very high capacity may be operated with facility.

My invention comprises means for obtaining great mechanical advantage, such means occupying a relatively small amount of space upon the base or switch board and extending relatively short distances into the region about the switch.

My invention comprises a construction wherein toggles connected in tandem are employed to operate the movable member of the switch, such toggles being so arranged and disposed that the operating member protrudes only a relatively short distance into the region surrounding the switch.

My invention consists also of a high capacity switch comprising a pair of terminals bridged by a plurality of movable members.

My invention comprises also means whereby switches as above described may be electrically controlled, either by the current passing through said switch or by current in any branch or in any other circuit.

My invention, in one of its forms, is illustrated in the accompanying drawings, in which:

Figure 1 is a side elevational view of an electrically controlled switch, in closed position. Fig. 2 is a front elevational view of the same. Fig. 3 is a side elevational view of the switch operating means, the toggles being in extended position. Fig. 4 is a view similar to Fig. 3, the toggles being shown in collapsed position. Fig. 5 is a fragmentary view in side elevation showing the auxiliary switch controlling the circuit of the tripping coil. Fig. 6 is a front elevational view of Fig. 5.

Fig. 7 is a plan view of the auxiliary switch. Fig. 8 is a diagrammatic view of the circuits of the switch. Fig. 9 is a diagrammatic view illustrating an overload tripping mechanism in connection with the switch herein shown and described. Fig. 10 is a diagrammatic view of the switch herein shown and described as adapted to be tripped on under-load or low voltage. Fig. 11 is a diagrammatic view of the switch herein shown and described as adapted to be tripped either on overload or reversed current flow. Fig. 12 is a fragmentary view, being a vertical elevation of the modified arrangement, in which the several bridging members co-operate with independent pairs of fixed contacts, for the purpose of controlling independent circuits.

Referring to the above mentioned drawings, B represents the usual base or switch board, of marble or other suitable insulating material. 1 and 2 represent the main terminal blocks of copper secured to the front of the base B by the bolts 3. The terminal blocks 1 and 2 are located one vertically above the other and have their contact faces in approximately the same vertical plane. Circuit connections are made to the terminals 1 and 2 at the extensions 4 and 5 respectively, from the front of the switch board. In case connections are to be made from the rear of the switch board such connections may be made to the body portion 1 and 2 of the contacts, and the extensions 4 and 5 may be omitted if desired.

6, 7 and 8 are independent laminated members adapted to bridge the main contacts 1 and 2. The laminated bridging member 6 is secured to but insulated from the vertically extending arm 9 pivoted at 10 in the bracket 11 which is secured to the base B.

12 is a bell crank lever, pivoted at 13 in the frame 11, the arm 14 being connected with the member 9 by means of the link 15 pivoted at 16 to the bell crank lever and at 17 to the member 9. The arm 14 and the link 15 constitute a toggle for cramping the bridging member 6 into engagement with the main terminals 1 and 2, as is well understood in the art. As shown in Fig. 1 the toggle 14, 15, is in extended position, the pivot 16 just falling short of being in the imaginary line joining pivots 13 and 17. The pivotal con-

nection 16 between link 15 and arm 14 is of the eccentric type for the purpose of adjusting the toggle 14, 15, as described in my application, Serial No. 63,690, filed June 8, 5 1901.

- Each of the laminated bridging members 7 and 8 is also operated by a toggle 14, 15, acting upon pivoted arms 9, 9, to which said laminated bridging members are secured.
- 10 The bell crank levers 12 of all these toggles are mechanically connected together by the horizontally extending rod or bar 18, whereby all the toggles of all the laminated bridging members may be operated simultaneously,
  - 15 the several adjusting devices at the pivots 16 serving to cause all the bridging members to exert practically equal pressures upon the main terminals. 19 and 20 are two similar levers pivoted at 10, concentrically with the arms 9, and including between them the operating handle 21. 22 is a link pivoted at 23 to the lever 19 and at 24 to the rod 18 which interconnects the bell crank levers 12. 25 is a link, similar to link 22, pivoted to the lever 20 at 26 and to the rod 18 at 27. The proportions and disposition of lever 19 and link 22 are such that when the toggle 14, 15, is in extended position as shown in Figs. 1 and 3, the pivot 24 falls a little short of being 30 on the imaginary straight line joining the pivots 10 and 23. In other words the lever 19 and link 22 constitute a toggle for operating upon the bell crank lever 12.

Fig. 3 shows both the toggles 19, 22, and 35 14, 15, in extended position, while in Fig. 4 the toggles are shown collapsed. The arrows in Fig. 4 show the directions of travel of the several parts when moving toward the circuit closing position of the switch. The 40 toggles 19, 22, and 14, 15, are connected in tandem, that is, toggle 19, 22, is connected with toggle 14, 15, in such manner that force applied at the handle 21 is transmitted through toggle 19, 22, and then through toggle 14, 15, to the laminated member 6. Obviously, each of the three toggles 14, 15, which operate the bridging members 6, 7, and 8, is connected in tandem with the primary toggle 19, 22, or 20, 25. From this it is 45 seen that the main or primary toggle 19, 22, operates upon the secondary toggle, 14, 15, the whole arrangement being a means for gaining very great mechanical advantage, or a force multiplying device. From the 50 fact that the toggles overlap each other, that is, the secondary toggles 14, 15, are so disposed and arranged with respect to the primary toggles 19, 22, or 20, 25, that their elements do not extend, more than an inconsiderable distance, beyond the region occupied or swept through by the primary toggles, the operator's handle protrudes from the switchboard a very much shorter distance than would be necessary in a case 55 where a simple operating lever, or a single

toggle were employed. By this arrangement the plurality of laminated bridging members may be simultaneously operated with reasonable ease by one person. Considerable force must be exerted to cramp a single laminated bridging member of ordinary dimensions against its contact terminals, and in the case of a high capacity switch of the type herein described the force necessary to cramp all of the laminated members into 70 engagement with their co-operating contacts far exceeds that available from one person, when switch closing mechanisms heretofore known are employed.

One of the bell crank levers 12 may have a 80 portion 28 extending beyond the bar 18 for the purpose of supporting the small roller 29 pivoted at 30. When the switch is in the circuit closing position the roller 29 is embraced and held by the latch 31, pivoted at 85 32 to the frame 11. The latch member has a downward extension 33 located in the path of travel of the armature 34 pivoted at 35, in the two iron cheeks 36, 36, forming the poles of an electro-magnet 37, extending horizontally 90 across the front of the apparatus. 38, 38, are stops on the armature 34 determining its position when unattracted. When a current is passed through the winding of the coil 37, or when the current in said winding is 95 increased to a predetermined value, the armature 34 is attracted by the pole pieces 36, 36, and rotates in a counter-clockwise direction about the pivots 35, 35, and delivers a 100 blow to the latch extension 33. This liberates the roller 29 from the latch 31 and simultaneously delivers a blow through the latch to said roller 29. In consequence the toggles 105 14, 15, and 19, 22 collapse under the influence of the blow and also under the influence of the springs 39 and 40 connected at one end to the levers 19 and 20 and at their other ends to the pins 41 and 42 secured in slight upward extensions 44 and 45 on the two outside bell crank levers 12, 12. The collapsing of 110 the toggles causes the withdrawal and fall of the laminated bridging members 6, 7 and 8 from the terminal blocks 1 and 2, the final position being that shown in Fig. 4.

46 is a resilient plunger mounted on the 115 bell crank lever 12, and adapted to receive the impact of the members 9 as it reaches its final open position the boss 47 engaging said plunger 46.

Secured to any one of the bell crank levers 120 12 (see Figs. 5 and 6) is a supporting bracket 48 whose two extremities 49 and 50 extend downwardly and partly embrace the rod or bar 18. Secured to these extremities 49 and 50, and insulated from them, is the brass or 125 copper bridging member 51 of an auxiliary switch having the end portions 52 and 53 serving to engage in the contact jaws 54 and 55 respectively. These jaws 54 and 55 are supported in the copper blocks 56 and 57, re- 130

spectively, mounted upon the slate or insulating pieces 58 and 59 secured to the bracket 11.

60 is a carbon shunt contact piece spring controlled and pivoted at 61 in a member secured to and extending vertically from the pivoted arm 9. The carbon 60 is in permanent electrical communication with the terminal block 2 through its support 62 and the flexible connection 63.

15 64 is a metallic contact piece secured to member 62 by the springs 65. Shunt contact piece 64 engages the face of the main terminal block 1, while carbon 60 engages shunt carbon 66 pivoted at 67 in a bracket secured to and in electrical communication with the main terminal block 1.

In opening, bridging members 6, 7 and 8 first break circuit, later 64 separates from 1, and finally carbon 60 separates from carbon 66, where the final arc occurs.

20 The path of the current through the switch may be as follows: The current may enter as by conductor 68, traverse terminal 1, bridging members 6, 7, and 8, terminal 2 and depart by conductor 69 (see Fig. 8). The current traversing the coil 37 may be derived from any suitable source through conductors 70 and 71. The circuit of the coil 37 may be controlled by a relay, an ordinary manual switch, an engine stop, or any other suitable means, such means being illustrated by the bridging member 72 adapted to engage the contacts 73 and 74. With the switch in the circuit closing position the bridging member 35 51 engages the contact jaws 54 and 55 and the circuit of the coil 37 is complete except at bridge 72. When, by whatever means, bridge 72 engages contacts 73 and 74, the armature 34 is attracted and the switch opened 40 as heretofore explained.

In Fig. 9, the main terminals and the bridging members are shown in side elevation. Embedded in the lower main terminal 2 is the magnetic mass 76 constituting with 45 said terminal 2 an electro-magnet whose armature 77, pivoted at 78 is attracted upon overload of current passing through the bridging members 6, 7 and 8, or any one of them. This arrangement of tripping magnet 50 is similar to that shown in my Patent No. 754,505, March 15, 1904. When said armature 77 is attracted the tail 77' engages the roller 29 and permitting the switch to open.

55 In Fig. 10 the main terminals and bridging members are again shown in side elevation. 79 is an armature carrying member pivoted at 81, the spring 82 tending to lift the member 79, carrying the armature 80. 84 is a 60 coil seen in end view and having pole pieces 83 to co-operate with the armature 80. The coil 84 is connected between conductor 69, and the conductor 69' forming the other conductor of the circuit. When the current 65 through the winding of the coil 84 diminishes

to a predetermined value, the spring 82 overcomes the attractive force between pole pieces 83 and armature 80, causing the member 79 to strike the tail of the latch 31, thus releasing the roller 29 and permitting the switch to open.

In Fig. 11 the main terminals and the bridging members are shown in side elevation. 76 and 77 are the same as described in connection with Fig. 9 for the purpose of actuating the latch 31 upon overload. To actuate the latch 31 upon the occurrence of reversed current or reversed energy flow, the member 85, which may be pivoted at 82, is provided. 86 is a member controlled by the 75 tilting member 91 which is acted upon by the coils 88 90 and 93, their cores being respectively 87, 89, and 92. 93 is a series coil while 88 and 90 are shunt coils connected across the main conductors 69 and 69'. 85 Upon reversed energy flow the member 91 rotates about the axis of the coil 93, and in a counter clock-wise direction thereby engaging the member 85 which then actuates the latch 31 to release the roller 29. This 90 reversed current tripping mechanism is similar to that shown in Patent No. 758,938 granted to me on May 3, 1904.

95 Referring to Fig. 12, 94 and 97 are a pair of main terminals adapted to be bridged by the member 6; 95 and 98 a pair adapted to be bridged by the member 7; and 96 and 99 a pair adapted to be bridged by the member 8. Each bridging member may therefore control a separate and independent circuit or 100 branch of a circuit, the operating mechanism being as hereinbefore described.

What I claim is:

1. In combination, fixed contacts, a plurality of members for engaging said contacts, a toggle for operating each of said members, and a toggle for operating said first-mentioned toggles.

2. In combination, a pair of fixed contacts, a plurality of independent members for engaging said contacts, a toggle for each member, means for interconnecting said toggles whereby said members are simultaneously operated, and means for engaging said interconnecting means for restraining said 115 members.

3. In combination, fixed contacts, a plurality of members for engaging said contacts, a toggle for each of said members, means for interconnecting said toggles, and a toggle for 120 operating said interconnecting means.

4. In combination, fixed contacts, a plurality of members for engaging said contacts, a toggle, and a force multiplying device intermediate said toggle and each of said members.

5. In combination, a pair of fixed contacts, a plurality of members for bridging said contacts, a toggle for operating each of said bridging members, means for interconnecting 125

1. said toggles, and a toggle for operating said aforementioned toggles.
2. In combination, fixed contacts, a plurality of laminated bridging members for engaging said contacts, a primary toggle, and a secondary toggle for cramping each of said laminated bridging members into engagement with its co-operating fixed contacts, said secondary toggles being connected in tandem with said primary toggle. 70
3. In combination, a pair of fixed contacts, a plurality of laminated members for bridging said contacts, a primary toggle, and a secondary toggle for cramping each of said laminated bridging members into engagement with said contacts, said secondary toggles being connected with said primary toggle. 75
4. In combination, fixed contacts, a plurality of independently pivoted members for engaging said contacts, a toggle for operating each of said members, and a toggle for operating said aforementioned toggles. 80
5. In combination, fixed contacts, a plurality of independently pivoted members for engaging said contacts, a toggle for operating each of said members, means for interconnecting said toggles, and a toggle for operating said aforementioned toggles. 85
6. In combination, fixed contacts, a pair of contacts located one vertically above the other, a plurality of laminated members for bridging said contacts, a toggle for cramping each of said laminated members into engagement with said contacts, and a toggle for operating said aforementioned toggles. 90
7. In combination, fixed contacts, a member for engaging said contacts, a toggle for operating said member, a second toggle for operating said first mentioned toggle, a connector between said toggles, and means engaging said connector for restraining said toggles in extended position. 95
8. In combination, fixed contacts, a member for engaging said contacts, a toggle for operating said member, a second toggle for operating said first mentioned toggle, a connector between said toggles, means engaging said connector for restraining said toggles in extended position, and electro-responsive means for controlling said restraining means. 100
9. In combination, fixed contacts, a pair of fixed contacts, a plurality of members for engaging said contacts, means for operating each member, a latching device for restraining all said operating means, and electro-responsive means for controlling said restraining means. 105
10. In combination, fixed contacts, a plurality of members for engaging said contacts, a toggle for cramping each of said laminated members into engagement with said contacts, a second toggle for operating said first mentioned toggle, and a spring connected between said toggles and operating to cause said toggles to collapse. 110
11. In combination, fixed contacts, a member for engaging said contacts, a toggle for operating each member, an element of each of said toggles having a bell crank extension, and a second toggle operating upon said bell crank extensions. 115
12. In combination, fixed contacts, a pivoted laminated member for engaging said contacts, a toggle for cramping said laminated member into engagement with said contacts, a second toggle for operating said first mentioned toggle and comprising an element pivoted concentrically with said laminated member. 120
13. In combination, fixed contacts, a plurality of pivoted laminated members for engaging said contacts, a toggle for cramping each laminated member into engagement with said contacts, an operating lever, and means connecting an element of each toggle with said operating lever. 125
14. In combination, fixed contacts, a pair of fixed contacts, a plurality of members for engaging said contacts, a toggle for operating each member, a latch for restraining said toggles, and electro-responsive means controlling said latch. 130
15. In combination, fixed contacts, a plurality of members for engaging

second toggle connected to said contact member, and another link of said first-mentioned toggle engaging said second toggle.

25. In an electrical switch, a pivoted movable contact member, an operating handle pivoted concentrically with said contact member, a toggle connected to said contact

member, and a link intervening between said handle and said toggle, said handle and link constituting a second toggle.

WM. M. SCOTT.
